UNITED STATES PATENT OFFICE.

CHARLES H. MYERS, OF BUFFALO, NEW YORK.

TRANSPARENT COVER.

1,126,257.

Specification of Letters Patent.

Patented Jan. 26, 1915.

Application filed March 23, 1910. Serial No. 551,057.

To all whom it may concern:

Be it known that I, CHARLES H. MYERS, a citizen of the United States, residing at Buffalo, in the county of Erie and State of New York, have invented a new and useful 5 Transparent Cover, of which the following is a specification.

The invention relates to improvements in covers for protecting and displaying goods 10 for advertising and other purposes.

The object of the present invention is to improve the construction of covers for displaying and protecting goods, and to provide an exceedingly simple transparent non-breakable cover, designed particularly for use in grocery stores, butcher shops and analogous places for protecting meat, fish, butter and various other articles of food, and capable of displaying such merchandise and 20 of simultaneously protecting the same from dust, dirt and insects.

Another object of the invention is to provide a transparent cover of this character, adapted to be readily constructed either for 25 ventilating the covered merchandise or for affording an air tight closure for the same when desired.

With these and other objects in view, the invention consists in the construction and 30 novel combination of parts hereinafter fully described, illustrated in the accompanying drawings, and pointed out in the claims hereto appended; it being understood that various changes in the form, proportion, size 35 and minor details of construction, within the scope of the claims, may be resorted to without departing from the spirit or sacrificing any of the advantages of the invention.

In the drawings:—Figure 1 is a perspective view of a transparent cover, constructed in accordance with this invention and shown resting directly upon a supporting surface. Fig. 2 is a vertical sectional view, the cover being arranged upon a pan supported in a 45 barrel for displaying a quantity of the contents thereof. Fig. 3 is a detail sectional view, taken longitudinally of a portion of the rim. Fig. 4 is a transverse sectional view of the same. Fig. 5 is a perspective view, showing another form of the invention. Fig. 6 is a vertical sectional view of the cover, illustrated in Fig. 5.

Like numerals of reference designate corresponding parts in all the figures of the 55 drawings.

In Figs. 1 to 4 inclusive is illustrated the

simplest embodiment of the invention, in which the cover comprises a transparent circular top plate 1, and a circular rim 2. The plate 1, which is arranged horizontally, 60 is constructed of flexible transparent material, such as thin celluloid, fibroid, or analogous pyroxylin products, and it is secured at its periphery to the upper edge of the circular rim 2 by means of inner fastening devices 3, consisting of tacks and piercing the transparent plate 1 at intervals and embedded in the rim 2, which is preferably constructed of wood. The attached edge of the circular plate 1 extends across the top of 65 the rim, and its periphery is flush with the outer side face of the same, and it is securely clamped on the rim by means of an annular strip or rim of metallic beading 4, secured at intervals by outer fastening devices 5, located at the spaces between the inner fastening devices 3, and piercing the metallic beading and the circular plate as clearly shown in Figs. 3 and 4 of the drawings. The beading presents lower engaging edges 70 at a plurality of points to the transparent top plate 1, which is firmly secured to the upper edge of the rim. It is composed of connected semi-spherical portions which are adapted to fit over and cover the heads of 75 the inner fastening devices. 80

The cover is equipped with a centrally arranged handle 6, having a threaded shank 7, piercing the top plate and upper and lower concavo-convex metallic plates 8 and 9, provided with flat peripheral portions 10 and 11, and clamped in engagement with the top plate by means of a nut 12, arranged on the threaded stem 7. The metallic plates 8 and 9 and the top plate 1 are provided with 85 registering perforations 13, 14 and 15, forming ventilating apertures, and the concavo-convex plates form interior spaces at the upper and lower faces of the top plate, with which spaces the said perforations communicate. The perforations may be omitted if desired to provide an air tight cover or closure. 90

In Figs. 5 and 6 of the drawings is illustrated another form of the invention comprising spaced upper and lower circular rims 16 and 17, a transparent connecting cylindrical wall 18, and a horizontal top plate 19. The transparent wall 18 and plate 19 are constructed of celluloid or analogous 100 material similar to the plate 1 heretofore described. The cylindrical wall is arranged 110

vertically, and is secured by upper and lower fastening devices 20 and 21 to the inner side faces of the upper and lower rims. The top plate 19, which is horizontal, is fastened to the upper edge of the outer end by inner and outer fastening devices 22 and 23, and a metallic reinforcing strip 24 of beading or the like, arranged as heretofore described. The cover, illustrated in Figs. 5 to 10 and 6 is also equipped with a handle 25, having a threaded stem 26 and provided with upper and lower concavo-convex clamping plates 27 and 28. The clamping plates 27 and 28 have flat peripheral portions and are held in engagement with the top plate 19 by means of a nut 29, engaging the threaded stem, as clearly shown in Fig. 6. The metallic plates 27 and 28 and the top plate 19 are provided with registering perforations 30, 31 and 32, forming ventilating apertures. Instead, however, of providing ventilating perforations at the center of the top plate around the stem of the handle, the thin transparent material may 20 be directly perforated at any desired point. The simplest form of the cover consists only of the top plate, and the wooden rim is adapted for use on lunch counters and analogous places for protecting pies, etc., 30 from dust and insects, and it may also be advantageously employed as a cover for a pan or receptacle 33, supported within the open top of a barrel 34 for displaying a quantity of the contents thereof, as clearly 35 shown in Fig. 2. The pan or receptacle 33, which is tapered, is adapted to fit tightly within and form a closure for barrels, varying somewhat in diameter, and the top plate 1 of the cover rests upon the edges of the 40 pan and is held in place by the weight of the rim, which constitutes a support or wall when this form of cover is employed for protecting pies, shallow dishes and the like. The form of cover illustrated in Figs. 5 and 45 6 may be made of any desired size for covering articles or merchandise of various proportions, and although only two rims 16 and 17 are shown, yet it will be apparent that when a relatively high cover is desired, 50 it may be reinforced at an intermediate point between the top and bottom by a cir-

cular rim or band. The cover is light and non-breakable, and in each form the rim or rims provide sufficient weight for retaining the cover in place.

Having thus fully described my invention, what I claim as new and desire to secure by Letters Patent, is:—

1. A transparent display and protecting cover including a circular wooden rim having a horizontal upper edge, a horizontal circular plate of thin, transparent, flexible, material, substantially as described, having its periphery arranged flat upon the upper edge of the rim, inner fastening devices 6 piercing the edge of the plate and entering the rim, an annular strip of beading arranged upon the plate in the vertical plane of the rim and over the said fastening devices, and outer fastening devices passing 7 through the beading and the plate and entering the rim, said beading being composed of a single continuous row of connected semi-spherical portions which cover and conceal the heads of the inner fastening devices. 7

2. A removable transparent display and protecting cover consisting of an upright cylindrical wall of thin, transparent, flexible material, substantially as described, upper and lower exterior wooden rims secured 8 to the said wall at the upper and lower edges thereof, the lower rim being flush with and forming a protector for the lower edge of the wall, a horizontal plate of thin, transparent, flexible material, substantially 81 as described, secured at its periphery to the upper edge of the upper rim and closing the space defined by the rim, a metallic reinforcing ring having fastening means piercing the transparent plate and embedded in the 91 upper rim, and a handle secured to the transparent plate and spaced from the upper rim, said cover being open at the bottom to allow the same to be placed over goods for protecting and displaying the same. 91

In testimony, that I claim the foregoing as my own, I have hereto affixed my signature in the presence of two witnesses.

CHARLES H. MYERS.
